INDICATOR SYSTEM**

David Lawrence Jaffe, Great Neck, N.Y., assignor to
Polarad Electronics Corporation, Long Island City,
N.Y., a corporation of New York
Filed Nov. 3, 1964, Ser. No. 408,478
13 Claims. (Cl. 340—339)

ABSTRACT OF THE DISCLOSURE

A message display system in which serially occurring data pulses control apparatus actuate alphanumeric devices to produce a continually moving, parade type display on the alphanumeric display devices.

This invention relates to a message display system and more particularly to a system for producing a message of alphanumeric characters in a parade type display in response to serially occurring information signals.

Many applications exist where it is desired to produce a moving message display. One familiar application is in a sign of the type where a number of characters move across the face of the sign to display information such as news, weather, etc.

The present invention is directed to a message or data indicator display system capable of continuously displaying visual information in a moving pattern. In accordance with the invention the data corresponding to the message to be displayed is produced by a suitable source in the form of serially occurring pulses. These are conveyed to the display unit of the system via a two wire telephone or telegraph line, a radio link, or any other suitable communication system. The display unit includes a number of alphanumeric character indicator modules arranged in a predetermined manner, for example side by side, for producing the desired moving message. These modules are controlled by the serially occurring data pulses in a predetermined manner to produce the desired moving message in a parade display.

In the preferred embodiments of the invention the alphanumeric character modules are of the electroluminescent type or other switchable luminous devices and formed by a number of segments which can be individually energized to produce a predetermined character, such as a number or letter. A storage medium receives a number of sets of serially occurring data pulses from the source and each set of the data pulses corresponds to one character to be produced on one character module. The storage medium and its associated apparatus first stores and then reads out each set of pulses in parallel to control one module. Each set is read out sequentially to produce a moving indication of the data on the character modules.

In the preferred embodiments of the invention the medium for storing the sets of serially occurring data pulses is a storage drum including a plurality of sets of glow lamps. This forms a relatively inexpensive storage device. Each set of lamps stores bits of information corresponding to one character of the message to be reproduced and each set of lamps is rotated past a number of readout stations which control the energization of a respective character module to produce a character. Rotation of the plurality of sets of lamps past all of the readout stations causes the characters to move sequentially from one indicator module to the next to produce a moving message display. In accordance with the invention an arrangement is also provided for transferring the data stored in the glow lamps of one drum to the glow lamps of another drum, thereby increasing the capacity of the system.

2

It is therefore an object of the present invention to provide a moving sign type of message or data display which operates from serially occurring data signals.

A further object is to provide a message or data indicator for displaying information in a moving pattern.

Another object is to provide a message or data indicator using electroluminescent or other luminescent type character modules which are controlled by serially occurring signals to produce a sequential parade type display of a message.

10 Still another object is to provide a data indicator for producing a moving message in response to serially occurring data signals received over a two wire transmission line, radio link, or other type of communications system.

15 Other objects and advantages of the present invention will become more apparent upon reference to the following specification and annexed drawings in which:

FIGURE 12 is a schematic diagram of a system using the drum of FIGS. 10A-10C and FIG. 11 for transferring data from one drum to another.

50 FIGURE 1 shows the type of moving message which is produced by the present invention. The message is formed by a number of visible characters, here illustrated by the letters POLAR of the word POLARAD. These 55 visible characters are part of a word unit 30 formed by six indicator character modules 35-1 . . . 35-6. Of course, the size of the word unit 30 may be increased as desired and a plurality of word units may be used.

55 The six indicator modules 35 of the word unit 30 are located side-by-side, as shown in FIGURE 1, to produce the moving message. Each indicator module preferably is of the alphanumeric type which is formed by a number of segmented light emitting elements. In a preferred embodiment of the invention the segments or elements are of the electroluminescent type. Indicator modules of this general type are currently available commercially, one suitable type being sold by Sylvania Electric Products, Inc., and another by General Electric.

60 In this type of indicator module a plurality of segmented electroluminescent elements, for example fifteen, of various sizes are arranged in a predetermined pattern, as illustratively shown in FIGURE 2 where the elements bear

corresponding reference numerals 1-15. By selectively energizing several of the elements 1-15 at the same time, a predetermined pattern corresponding to letters and numerals can be formed. Throughout the remainder of the specification and in the claims the term "character" is used to designate letters, numerals and punctuation marks producible by the system on a character indicator module. While a fifteen element indicator module is shown, other suitable types may be used, for example, the twelve element module shown in Sinninger Patent 3,081,450. It is preferred that the segmented elements to be illuminated be of the type which can be energized through low current switches. Of course, other types of indicator modules may also be utilized, for example, those using a plurality of neon tubes, incandescent tube lamps or banks of incandescent lamps. All of these would be arranged in a pattern on the order of that in FIGURE 2 to enable all letters and numerals to be produced.

As can be seen from FIGURE 2, any character can be formed by energizing the proper segments of an indicator module 35. For example, elements 1, 2, 3, 4, 5, 8 and 12 would be energized to produce the letter A. To produce the letter B, elements 1, 2, 3, 4, 5, 6, 8 and 12 would be energized. Other letters and numerals are formed in a similar manner. Element 15 is for a period.

A chart can readily be prepared to show the energization pattern of the elements to produce the desired character. The preparation of this chart merely requires determining the outline of the desired character and listing the elements of the particular indicator module being used which must be energized to produce it. The information derived from such a chart is used to operate switching elements to control the energization of the indicator modules 35 in a word unit 30 in a manner which is described in detail below.

By energizing the respective individual indicator modules 35-1 . . . 35-6 of a word unit 30 in sequence with successive characters of the message, a parade type display is produced which gives apparent motion to a message. To illustrate, consider that the first letter P of the illustrated word successively moves from indicator module 35-1 to module 35-2, etc. Each succeeding letter of the word follows behind the letter P and a message with apparent motion from right to left is produced. Of course, the indicator modules 35 remain stationary.

It should be understood that a plurality of word units 30 formed by six or more character indicator modules 35 can be arranged side by side to produce longer messages. A system utilizing two such word units 30-1 and 30-2 is shown in block diagram form in FIGURE 3. It should be understood that this system may be enlarged to use additional or larger size word units as desired. Before describing this system reference is made to FIGURE 4 which is a diagram illustrating the types of signals used to operate the system.

As shown on line A of FIGURE 4, each character frame time, i.e., the interval during which information corresponding to a single character is produced, is divided into twenty-two periods. Each period is divided in half giving a total of forty-four half periods or spaces and each of the twenty-two periods is schematically represented on line A of FIGURE 4 by a positive going pulse appearing during the first half of each period (odd numbered space) and then the absence of a pulse during the second half of each period (even numbered space). For convenience of description, the forty-four spaces of each character frame time are numbered 1 through 44 on line A.

As shown on line B of FIGURE 4, a negative going start pulse is produced during the first half of each of the first four periods, that is in spaces 1, 3, 5 and 7. If desired, the series of four start pulses may be replaced by a continuous start pulse occupying the first seven spaces. The fifth through twenty-second periods, as shown on line C, each has a positive going sync pulse during

the first half of each period, i.e., at the odd numbered spaces 9 to 43. This makes a total of eighteen sync pulses. The information signals occur as negative going pulses during the second half of the fifth through twenty-second periods, that is, at the even numbered spaces 10 through 44. This is shown in line D which is a representation of the composite signal of start, sync and information pulses used to operate the system. It should be understood that the selection of the polarities and spacing assignment for the various pulses of the composite signal is optional and that any desired arrangement may be used.

In line D of FIGURE 4 information pulses corresponding to the letter A are shown so that the negative information pulses occur during the second half of the fifth, 15 sixth, seventh, eighth, ninth, twelfth and sixteenth periods, i.e., even numbered spaces 10, 12, 14, 16, 18, 24 and 32. Stated another way, each negative pulse occurs at the indicator module element number of FIGURE 2 plus four and one-half periods or nine spaces. The shift of nine spaces is occasioned by the start pulses during spaces 1, 3, 5 and 7 and the first sync pulse at space 9. It should be understood that the information signals for other characters would occur during the odd numbered spaces of the second half of periods of the composite signal 20 25 corresponding to the module elements which are to be energized to produce them plus the nine space shift.

Referring again to FIGURE 3, the composite signal of line D, FIGURE 4 is produced by a suitable source 40, which will be described in detail below, and applied 30 to a sync separator 42. Sync separator 42 separates the start, sync and information pulses from the composite signal of FIGURE 4. This is done quite readily by a pair of biased diodes which pass pulses above or below the reference level about which the composite signal 35 fluctuates.

The start pulse or pulses from sync separator 42 are applied to latch relays 44-1 associated with word unit 30-1. Latch relay 44-1 operates a mechanical latch 45 which physically engages the corresponding memory 40 drum 47 or an auxiliary portion thereof to prevent it from rotating. When relay 44-1 is energized it picks up latch 45-1 and frees the drum 47-1 for rotation by a stepping type motor 48-1.

The sync pulses from separator 42 occurring after the start pulse are applied to a respective motor amplifier 49-1 for controlling the action of the stepping motor 48-1 in a synchronized manner. The serially occurring information signals from separator 42 are applied to a commutator 50-1 in the first word unit 30-1. Commutator 50-1 distributes the information signals to be stored by memory drum 47-1 in a manner such that they may be read out at a later time.

Information stored on memory drum 47-1 is read out and applied through a switch 52-1 to operate indicator 55 modules 35-1 . . . 35-6 of word unit 30-1. As will be described in greater detail below, each set of information signals corresponding to a character is read out and used to energize the elements of one of the modules 35 to visually reproduce the character. As the drum 47-1 is 60 rotated, each set of signals corresponding to a character, is successively moved to a different readout station to control a different indicator module. The visually reproduced character therefore moves from module to module and from right to left in the system of FIGURE 3. When 65 drum 47-1 contains six sets of signals all six modules 35-1 to 35-6 will be energized simultaneously.

The drum 47-2, commutator 50-2, and switch 52-2 operate in the same manner to control the energization of modules 35-7 . . . 35-12 of word unit 30-2. However, 70 instead of commutator 50-2 receiving the start and information signals from sync separator 42, these are supplied from the commutator 50-1 by a transfer device 53 to be described later. Transfer device 53 receives serially the set of information signals previously used to energize module 35-6 and applies them through an amplifier 75 54

to commutator 50-2 to control the energization of module 35-7. This transferred set of signals moves along with the rotation of drum 47-2 to sequentially control the energization of modules 35-8 through 35-12. The start pulse or pulses for operating latch relay 44-2 are produced by the operation of both the drum 47-1 and data source 40 and the sync signals to operate stepping motor 48-2 are produced by the data source 40, as will be described in detail below. Thus the rotation of both drums 47-1 and 47-2 is fully synchronized. If desired, the two reader drums 47-1 and 47-2 may be placed on a common shaft so that only a single motor 48, latch 45 and latch relay 44 will be needed. However, the latter arrangement does not facilitate modularization of the word unit 30 so that a plurality of these units may be readily connected together to increase the message capacity.

Transfer device 53 also effectively erases the last set of signals from drum 47-1, which were previously used to operate module 35-6, to permit a new set to be stored to control module 35-1. Thus, there is a continuous transition of the sets of signals from word unit 30-1 to word unit 30-2 so that the message flows steadily. This arrangement can be extended for additional word units as desired.

One embodiment of data and sync source 40 for producing the composite signal of FIGURE 4 is described in detail below. This embodiment uses a keyboard to select a desired character, in the manner of a typewriter or teletypewriter, and a plurality of rotating drums. Each drum has a plurality of light transmissive openings therein in predetermined patterns which pass under a respective bank of photoconductive switches. The openings in the drums are made to selectively emit light so that the composite signal of FIGURE 4 may be produced for any desired character.

FIGURE 5 is a developed view of one of the rotatable drums 60 used for producing the composite signals of FIGURE 4. Three such drums are provided, each having different patterns of openings therein. Since the drums are similar, only one drum 60-1 is described in detail. Drum 60-1 has an opaque outer surface provided with a plurality of tracks having a number of light transmissive openings therein in a predetermined pattern. Illustratively, fifteen tracks of openings are provided for producing various types of start, sync and character information. Each track is divided into twenty-two portions, corresponding to the twenty-two periods of the timing cycle of FIGURE 4 and openings 61 of a half period (space) duration are made at predetermined places in certain of the tracks. The length of each of the openings 61 corresponds to the time and one-half a period during rotation of the drum and each opening is spaced on the drum at a position corresponding to the first or second half of the period (odd or even numbered space) to produce a signal at that time. As shown, each track extends for a full 360° around the periphery of the drum.

Each drum may be provided with as many tracks per section and openings per track as needed. As shown in FIGURE 5, the drum is provided with a start track 60ST, a sync track 60SY, and thirteen information tracks 60I. Each information track has a pattern of openings 61 cut therein corresponding to the pulses to be produced to form the information code of FIGURE 4, line D.

Located under each track of openings is a separately energized and stationary light source, or sources, which is shielded from the light sources of the other tracks by any suitable means, such as a light baffle. In a preferred embodiment of the invention a glow lamp is preferably positioned adjacent the undersurface of the drum for each track so that each track has a corresponding lamp as a source. By selectively energizing one or the other of the lamps adjacent a corresponding information code track 60I of the drum, the openings of that track have light passing therethrough as they pass by the energized lamp. This light energizes a photoconductive cell which,

acting as a switch, converts D.C. power into signal pulses in a signal processor as the drum is stepped around. The lamps for the sync and start pulse tracks 60ST and 60SY for each drum 60 are energized each time that a lamp is 5 for one of the information tracks is energized. This is described in greater detail below.

Each drum has the start, sync and information codes distributed over 360° of its periphery. Starting with the rightmost track of the drum 60-1 being described in FIGURE 5, a series of openings 61 is provided at the positions corresponding to the first half of each successive period from the fifth through the twenty-second (odd numbered spaces 9 through 43). These openings correspond to the sync pulses. In the second track from the right the first four periods have openings during the first halves of the first four periods (spaces 1, 3, 5 and 7) for producing the start pulses. If desired, a continuous opening may be provided for the first seven spaces. The first thirteen information tracks 60I from the left have openings therein during the second halves of the fifth through twenty-second periods (even numbered spaces 10 through 44) in a predetermined pattern corresponding to the information for various characters. As shown in FIGURE 5 the patterns of openings in the thirteen information tracks correspond to a period (.) and the letters A through L.

If desired, a track containing auxiliary information, called a "spare" track, may be provided. This spare track (not shown) may have any desired pattern of openings provided therein. It may be used for an end of character signal, additional sync pulses, end of line, end of message pulse signals, etc. It should be noted that in the preferred embodiment of the invention being described that periods twenty through twenty-two of the frame time 35 are not used for character information since only a fifteen element character module is utilized. These three periods may be used for "spare" information. Also, the "spare" information may be inserted into the other periods and readily distinguished by the use of suitable 40 modulation techniques for the "spare" signals.

It should be understood that the other two drums are formed in a manner similar to that of FIGURE 5. However, in these drums the pattern of openings in the information code tracks 60I correspond to the signals 45 needed to reproduce the other characters M through Z, the numerals 1 through 9, and miscellaneous characters and punctuation. The patterns of openings 61 for the start, sync and spare tracks, if one is used, are the same.

The drum 60-1 of FIGURE 5 has twenty-two periods 50 so that each step of the drum by a stepping motor is approximately 16.36° to produce a full 360° rotation in twenty-two steps. As the drum 60-1 is stepped around, the illuminated openings of one track having the information for the character selected to be reproduced at a 55 module 35, in addition to the illuminated openings of the tracks for the start and sync pulse information, pass underneath a bank of photoconductive cells 65. The selected character information, in addition to the information for the start and sync pulse, is read out by the photoconductive cells which form part of a signal processor 60 for converting the information read by the cells into the composite signal of FIGURE 4.

FIGURE 5A shows an arrangement for energizing the light sources of a drum. Only a few of the light sources 65 for one of the drums 60 is shown and it should be understood that the energizing arrangement applies to all of the light sources of all of the drums. In FIGURE 5A a lamp 63 is located within the drum adjacent the start track 60ST while a lamp 65 is located in the drum adjacent the sync track 60SY. A separate lamp 68, through 70 68-L is located in the drum adjacent each one of the character information tracks 60I.

The various lamps 63, 65 and 68 are stationary and are located at positions within the drum so that light produced thereby shining through a respective opening 61 in

a track adjacent an illuminated lamp impinges upon a corresponding photoconductive cell located opposite each track in a detector bank 65-1. Adjacent the start track is a photoconductive cell 73; adjacent the sync track is a photoconductive cell 75; and adjacent the information track corresponding to the characters are respective photoconductive cells 79, through 79-L.

Only two lamps 68, and 68-L are shown for the character information tracks 60I. These two lamps are located within the drum adjacent the two tracks having openings therein in a pattern corresponding to a period and the letter L respectively. The production of the opening patterns was described previously. The other character information tracks (not shown in FIGURE 5A) have stationary lamps 68-A through 68-K (not shown) located within the drum adjacent the corresponding tracks having patterns of openings therein for the letters A-K. Similarly, a respective photoconductive cell 79-A through 79-K is provided in the detector bank 65-1 opposite the opening patterns for the respective character information tracks corresponding to the letters A through K. A photoconductive cell is also provided adjacent the spare track, if one is used, but neither this cell nor the corresponding lamp or track are shown in FIGURE 5A for the sake of clarity. The outputs of the respective photoconductive cells 73, 75 and 79 go through a signal processor 90 which forms the composite signal of positive and negative pulses. The processor is described in greater detail below.

As shown in FIGURE 5A, all of the lamps 63, 65 and 68 for the start, sync and information tracks are wired in parallel directly across the B+ supply and ground. This supply is not shown in any of the drawings or described further but it is formed by any suitable power supply unit, many of which are conventional in the art.

One side of each character information track lamp 68, through 68-L is connected directly to a corresponding lamp trigger line 85, through 85-L. A common trigger line 85SS is connected to one side of each of the lamps 63 and 65 through the respective capacitors 66a and 66b and the capacitors are returned to ground by a discharge resistor 67. The other side of the lamps 63, 65 and 68 are connected in parallel to the B+ supply through line 86 and the contact of a normally closed relay K2. Relay K2 is used to deenergize the illuminated lamps 63, 65 and 68 at the end of each character frame by removing B+ therefrom. The side of each lamp 63, 65 and 68 adjacent a respective lamp trigger line 85 is connected through a resistor 70 to a suitable source of reference potential such as ground 71. Since the various lamps 63, 65 and 68 are stationary, there is no need to use slip rings or a commutator. While the various power supply lines and trigger lines are shown schematically as extending through the drum, they actually go out from the interior of the drum through one open end thereof.

During a character frame time, depending upon which trigger line 85 receives an energizing or trigger signal, the lamp 68 connected to that particular trigger line is illuminated. All of the other character lamps 68 are left dark during the frame time under consideration. Each of the lamps 68-—68-L is positioned substantially opposite the corresponding photoconductive cell 79-—79-L so that when an opening in the drum passes by the selectively illuminated lamp 68, light shines through the opening onto the corresponding photoconductive cell 79. No light emanates from the openings in the drum tracks corresponding to all the other characters whose trigger lines did not receive a trigger signal since the lamps for these tracks are dark. Since lamps 63 and 65 are triggered on each time one of the lamps 68 is energized, light passes through the openings in tracks 60ST and 60SY to the corresponding photocells 73 and 75 as the drum rotates.

As the drum 60-1 is stepped through 360° in twenty-two steps, the corresponding photoconductive cells adjacent the start and sync tracks and the selectively energized lamp 68 of an information track, each receive a pulse of

light whenever an opening in a track passes by an illuminated lamp. The photoconductive cells 73, 75 and 79 are preferably of the cadmium sulfide, or other similar, type having a high dark (no light) resistance and a low resistance when light is impinging thereon. Each of the photoconductive cells in the bank 65 is separated by a suitable member 81 or placed in a light-tight housing so that no light is received from an adjacent track.

The photoconductive cells of bank 65-1 are connected to a signal processor 90. The processor includes a resistor 91 which is connected in series with the B+ supply, another resistor 91a and the photoconductive cell 75; a resistor 93 connected in series with the B+ supply; another resistor 93a and photoconductive cell 73; and a third resistor 95 connected in series with the B+ supply, another resistor 95a and the parallel connected photocells 79- through 79-L. If desired, and if placing too many cells 79 in parallel lowers the overall resistance too much, then the cells 79 can be split up into banks and connected to separate resistors 95 whose output leads would be connected together.

Each time a photoconductive cell receives a pulse of light through an opening of the moving drum the resistance of that cell decreases to a relatively low value. This completes the series circuit for the corresponding connected resistor 91 or 93 or 95 to the B+ supply and permits current to flow through the resistor thereby producing a positive going voltage drop across the resistor. The magnitudes of the voltages supplied from the B+ source are selected, such as by the use of suitable voltage divider resistors, to produce the proper magnitude output pulses across the resistors 91, 93 and 95. Thus, positive going pulses, corresponding to the sync pulses, are produced at the upper end of resistor 91 during the first half of each of the fifth through twenty-second periods; positive going pulses, corresponding to the information code, are produced at the upper end of resistor 95 during the second half of each of these periods when an opening appears in an information track 60I; and positive going pulses, corresponding to the start pulses, are produced across resistor 93 during the first half of each of the first four periods.

As shown in FIGURE 5B the upper end of the resistor 91, having positive going pulses thereon for the sync, is applied to a follower type amplifier 90a whose output is also positive going pulses. The upper ends of resistors 93 and 95 having positive going pulses thereon for the start and code information respectively, are connected to a mixer and inverter amplifier 90b. Here, the signals from resistors 93 and 95 are mixed together and inverted into negative going pulses. The positive going sync pulses from follower amplifier 90a and the negative going start and information code pulses from inverter mixer amplifier 90b are applied through respective relay contacts K1a and K1b to the inputs of a non-inverting mixer 90c. The two input signals are mixed here without inversion and the composite output signal of FIGURE 4 line D is produced at the mixer 90c output.

It should be understood that three drums and three detector cell banks 65, similar to those described in FIGURES 5 and 5A, are provided. The patterns of openings for the character information tracks 60I of drum 60-2 and 60-3 are different and correspond to the letters J through Z, the numbers 1 through 9, and any miscellaneous punctuation desired. Each drum 60 has a sync and start track. Since three drums are utilized, the character information for drum 60-1 may correspond, for example, to a period and the letters A-L; for drum 60-2 to the letters M-Y; for drum 60-3 to the letter Z, numbers 1 through 9, and any miscellaneous punctuation. Of course, there is no need to place the opening patterns in alphabetical or numerical order on each of the drums as described above. Any suitable arrangement may be used and the characters, including letters, numerals and punctuation, may be mixed on each drum in any desired manner to facilitate the switching circuits needed to selectively trig-

ger one of the lamps 68 during any one character frame time. It should also be understood that the track capacity for each drum may be selected as desired to increase or decrease the number of drums 60 needed to produce all of the desired characters.

Each of the drums 60-2 and 60-3 also has a corresponding cell bank 65-2 and 65-3. These cell banks are similar to bank 65-1 and the photoconductive cells therein are all connected to the signal processor 90 in parallel with the corresponding photoconductive cells of the other cells banks. If desired, a separate processor 90 can be used for each cell bank and the outputs thereof connected in parallel to the inputs of the amplifiers in the processor 90.

FIGURE 6 shows one form of data source 40 for selectively energizing the lamps 68 of the drum 60 of FIGURE 5A by a keyboard arrangement 110. Here, the keyboard 110 is provided with a plurality of spring loaded double-pole double-throw switches 112-1 . . . 112-n whose movable center arms are mechanically ganged together. As many switches 112 are provided as are needed to select the individual characters for reproduction by the indicator modules, with some of the switches being able to selectively energize two lamps 68 in order to increase the capacity of the keyboard without making the number of switches 112 unwieldy.

The contact of the center movable arm of the right-hand half of each switch 112 is connected to the one end of a respective capacitor 118-1 . . . 118-n, whose other ends are all connected to the upper end of a resistor 119 and diode 119a connected in parallel. The lower end of the resistor-diode network returns to ground. With each movable center arm of the righthand half of a switch 112 in its normal rest position engaging the right-most stationary switch contact, the respectively connected capacitor 118 charges to a B- potential over a line 120 connected to all of the right-most stationary switch contacts.

Each time one of the switches 112 is depressed, the right-most center arm is moved to the adjacent left stationary contact. This produces a trigger spike at the resistor-diode network 119-119a which is conveyed over line 116 to a relay amplifier 115. Diode 119a prevents negative going spikes from reaching the amplifier by passing such spikes to ground. The relay amplifier 115 controls the energization of a relay K1 to start a cycle of production of the composite signal.

The left stationary contact of the right-hand section of each switch 112 is connected to a respective lamp trigger line 85. Hence, when a selected switch 112 is depressed, the negative charge on the respectively connected capacitor 118 is applied directly to one side of the connected lamp 68 adjacent the selected character code track 60I. The left-most contact of the left hand section of each switch is connected over line 120 to the B- supply while the center movable contact of the same section of each switch is connected to the sync start trigger line 85SS of one of the drums 60. As shown, the upper bank of switches go to line 85SS-1 of drum 60-1, the middle bank to line 85SS-2 of drum 60-2, and the lower bank to line 85SS-3 of drum 60-3. Of course, any suitable wiring arrangement may be used as a matter of choice, but the connected trigger line 85SS must be to the same drum on which is located the lamp 68 for the selected character corresponding to the switch 112 that is depressed. The movable contact of the left switch section applies B- directly to a trigger line 85SS when a switch 112 is depressed.

Several of the switches 112 have their respective left stationary contacts on their right hand section connected to the center arm of a relay K3 which is energized by a normally open switch 113. The movable contact of switch 113 is connected to a suitable source of B+ potential 113A having one end thereof connected to ground. When the switch 113 is closed the relay coil of relay K3 is energized and the movable contacts K3-a . . . K3-n are moved between two stationary relay contacts having lamp

trigger lines 85 connected thereto. Thus, several of the switches 112 have the capability of selecting two lamp trigger lines 85 depending upon the condition of switch 113, which switch is normally open. Switch 113 corresponds to the shift key of a standard typewriter or teletypewriter keyboard. It should be understood that as many of the switches 112 can be connected for operation with relay K3 as desired, thereby giving each switch so connected the capability of selecting two trigger lines, corresponding to two characters, in accordance with the condition of switch 113.

The three data source drums 60-1, 60-2, and 60-3 are rotated on a common shaft 147 by a stepping type motor 148. Motor 148 may be, for example, of the type designated Slo-Syn, manufactured by Superior Electric Company. Motor 148 is adjusted to step 360° in 22 steps in response to switching pulses produced by a pulse generator switching pulses produced by a pulse generator 142. If desired, a continuously rotating motor may be used with a suitable arrangement, such as a ratchet and pawl, for producing stepping action.

The operation of the data source of FIGURE 6 is as follows. Moving the center ganged arms of any of the switches 112 to the left applies a positive trigger from the resistor-diode network 119-119a onto line 116 to energize a relay amplifier 115. When amplifier 115 is made conductive it energizes relay K1 thereby lifting a mechanical stop 130 out of a notch 131 provided on a disc 132-1 which is connected to and rotatable with the common shaft 147 of drums 60. The stop 130 would normally serve to prevent the drums 60 from rotating unless this stop was taken out of the notch 131. The notch 131 is in registry with the 0° point of each drum 60, i.e., the notch is aligned with the beginning of the start track of each drum.

When relay K1 is energized the composite signal line contacts K1a and B1b of the processor 40 (FIG. 5) are closed as well as a lower contact K1c. The lower contact K1c applies a trigger spike from a resistor 141 and capacitor 141a over line 140 to a triggered pulse generator 142 which controls the operation of the stepping motor 148. Once generator 142 starts to produce the pulses, which occurs upon application of a trigger over line 140, stepping motor 148 operates and starts to rotate the drums. Upon rotation, the mechanical stop 130 lifts up on the outer periphery of the disc 132-1 and the contacts of relay K1 remain closed during the 360° rotation of the drums until the stop 130 falls back into the notch 131. Because of this mechanical closing of relay K1 contacts it is not necessary to keep relay amplifier 115 conductive.

As a switch 112 has its center arms moved into contact with the respective left stationary contacts, its respective capacitor 118 is discharged through resistor 119. As explained above, this energizes K1 through relay amplifier 115 and lifts the mechanical stop 130 setting the pulse generator 142 into operation. At the same time B- voltage is applied directly from the leftmost stationary contact to the trigger line 85SS connected to the center contact of the actuated switch. This causes lamps 63 and 65 connected to the energized trigger line 85SS to fire. Also, the charge on the respective capacitor 118 of the actuated switch 112 is connected via the center arm of the right half switch section to the left stationary contact of the same section of the switch 112 and through this contact to the connected lamp trigger line 85 and corresponding lamp 68 selected by the particular switch 112 which was operated. The pulse discharge of a capacitor 118 causes the lamp 68 connected to the trigger line 85 receiving the pulse to fire. It should be understood that the B+ applied to one side of a lamp 68 through relay K2 is not sufficient to fire the lamp but is sufficient to maintain it once the lamp is fired. However, the combination of pulse polarity potential produced by discharge capacitor 118 when applied to a selected trigger line 85 onto one side of a selected lamp bank and the B+ bias applied to the other side of the lamp causes it to fire.

When the pulse from the capacitor is removed, the lamp still remains fired until the supply voltage from relay K2 is removed. The same holds true with respect to the operation of lamps 63 and 65 which receive a negative trigger over line 85SS.

As the motor 148 steps the drum through a 360° rotation cycle, the photoconductive cells produce a composite signal in the manner described with respect to FIGURE 5A. The composite signal at the output of the processor 90 is obtained through the relay contacts K1a and K1b which are used in conjunction with a non-inverting mixing amplifier 90c.

After the drums 60 have been rotated for 360° the mechanical stop 130 falls into the notch 131, thereby stopping the rotation of the drum. As pointed out before, relay amplifier 115 is only energized initially to close relay K1 and permit rotation of the drum. Also the pulse generator does not provide any more pulses to the step motor 148, because it generates only 22 of these at a time and only after it has been triggered over line 140.

A second disc 132-2 is also connected to and rotatable with the drums 60. Disc 132-2 has one projection 135 located thereon which is advanced with respect to the notch 131 of disc 132-1 by a small angle, for example about 5° or 10°. Projection 135 has a small angular width, for example about 2°, and is adopted to open the contact of normally closed relay K2. Thus, near the end of each rotation of the drums the projection 135 opens the contact of relay K2 and removes the B+ from the line supplying the lamps 63, 65 and 68. This serves to extinguish the lamps which were fired at the beginning of the cycle.

The keyboard 110 also has a switch 114 which serves as a space control. When switch 114 is closed by moving the center arms to the leftmost contacts, the step motor 148 is energized to rotate the drum 60 as described above. However, in this case only one lamp 65 and one lamp 63 are energized but none of the lamps 68 is energized so that only the sync and start pulses are produced in the composite signal from the output of the processor 90.

The composite output signal from the processor 90 of FIGURE 5B is transmitted to a "reader" station for producing a display of the type shown in FIGURE 1. Any suitable transmission medium can be used, for example, a transmission line, microwave or radio link, or a direct coupling where the composite signal producing system and the reader station are located in the same place. While the composite output signal of the processor 90 of FIGURE 5B is shown on a single line at the output of the non-inverting mixer 90c, it is considered for purposes of explanation that the composite signal has been placed on two output lines with the positive going signals on one line and the negative going signals on the other. This is shown in FIGURE 7, which is a block diagram of the reader station, in which two terminals 200 and 201, respectively, receive the positive and negative signals. The composite signal can be separated into positive and negative components by a sync-separator (not shown) preceding the terminals 200 and 201 at the reader station or by a sync-separator at the source producing the composite signal, i.e., the data source 40 of FIG. 1.

The reader station of FIG. 7 includes a rotatable memory or reader drum 47. Since the bit storage capacity required of the complete system is relatively small, the reader drum preferably uses an electromechanical and optical storage technique rather than the more widely used electronic (e.g., tube or transistor) or magnetic (tape, cores) techniques. Reader drum 47 is divided into six segments, hereafter referred to as segments one through six, and each reader drum segment occupies 60° out of the available 360° of the drum's surface. Each segment contains a bank of storage elements, preferably neon lamps, and the elements are energized through a commutator to store information pulses transmitted from the data source in a pattern corresponding to the character to be visually reproduced on a character indicator

module 35. Six stationary reader stations, hereafter called stations one through six, are also provided and these stations contain apparatus for sensing the stored information and the switches needed to control the energization of the segmented elements through 15 of a respectively connected character indicator module 35-1 through 35-6.

To continue with the description of the reader station, the negative going signals (start and information pulses) are applied through a suitably poled diode 205 to the input of a start pulse detector 207 and a write amplifier 209. The start pulse detector detects the characteristic start pulses (see FIG. 4), which may either be a continuous long pulse or a series of pulses, transmitted during the first four periods of a character frame time. When a start pulse has been detected, indicating the beginning of a character frame, detector 207 produces an output signal which is used to energize a relay K4. Relay K4 has a detent 220 whose follower rides on the periphery of a cam 222 and drops into notches 223 spaced 60° apart around the cam periphery. The notches 223 and the detent 220 follower are relatively sharp so that the follower can be removed rapidly from the notch. Cam 222 and two other cams 232 and 242 are mounted on the shaft 217 of reader drum 47 and rotate therewith in the direction shown by the arrows.

When the follower of detent 220 is in one of the notches 223 of cam 222, reader drum 47 is prevented from rotating. This is a mechanical stop and the drum can only rotate after the follower is lifted out of notch 223. This occurs when a start pulse signal is received and relay K4 is energized picking up the detent. Energizing relay K4 closes its normally open contacts and applies B+ from any suitable source to a ring counter 250. Counter 250 corresponds to the motor amplifier 49 of FIG. 1. The input to the ring counter are the sync pulses applied through a suitably poled diode 206. Ring counter 250 produces an output count shifted by one in response to each successive input sync pulse. Counter 250 is of any suitable conventional construction. As shown, it has four output lines on which the counter output pulses appear and a fifth line which is a common return for the four output lines.

The two upper and two lower output lines of the ring counter 250 are respectively connected to the ends of the armature coils 261 and 262 of stepping motor 48 which is preferably of the same general type previously described for the data source and may be the aforementioned Slo-Syn motor. The middle, or common, line of the ring counter is connected to the common point of the motor 48 by tapping coils 261 and 262 at the center points thereof. The construction of the motor 48 is such that upon each advance of a count by one of the ring counter 250, the motor is moved one step. In a preferred embodiment of the invention, motor 48 is adjusted to provide 108 steps for a 360° revolution. Each 360° revolution is divided into segments of 60°, after which detent 220 falls into a corresponding notch 223 preventing further rotation of the drum. Thus, after being energized by the start pulse, counter 250 moves the motor eighteen steps, in response to the eighteen sync pulses received from the composite signal of FIGURE 4, before the detent 220 falls into notch 223, and prevents further drum rotation. This rotates drum 47 and the attached cams 222, 232 and 242 by 60° in eighteen steps of 3 1/3°.

At the same time drum 47 is being rotated, information, or write, signals are applied through diode 205 to a write amplifier 209. These write signals are amplified and applied over line 210 to a commutator 270 having 108 segments over its 360° periphery. Commutator 270 corresponds to commutator 50 of FIG. 1, but the new reference numeral is used for the sake of clarity. The 108 segments of the commutator corresponds to six commutator portions having eighteen segments per portion. The various segments of the commutator 270 are connected to lamps of the reader drum, as is described below.

Cam 232 mechanically operates the normally closed contacts of a relay K5 having a detent 230 with a follower which falls into notches 233 on the cam periphery. There are six of the notches 233 spaced 60° apart, and they are designed so that the detent 230 opens the contacts of relay K5 after approximately 10° of the rotation of drum 47. When the contacts of relay K5 open B+ is removed from the start pulse detector 207, thereby deenergizing relay K4. However, B+ is applied to counter 250 through the contacts of relay K4, which are closed mechanically since the detent 220 is riding on the raised periphery of the cam 222 holding the relay contacts closed.

Since the storage capacity of the reader drum 215 is not infinite, an arrangement is provided to erase the information contained in the last segment of the drum after it is used. This information was used to energize the last module 35-6 of word unit 30. Erasing is accomplished by a sensing and erasing circuit 275 whose input-output is taken from and applied to the commutator 270 one commutator segment in advance of the input to the commutator from write line 210.

The sense portion of circuit 275 senses the condition of the individual lamps of the drum 47 and actuates the erase circuit to extinguish a lamp each time one is sensed as being lit. Whenever a lamp of the drum 47 is lit, it corresponds to the receipt of an information signal meaning that the element of a character module 35 corresponding to that lamp is to be energized.

Six stationary reader stations, corresponding to the six segments of drum 47 and the six character modules 35 of a word unit, are disposed 60° apart around the outer periphery of the drum 47. Each reader station contains sensing elements, preferably photoconductive cells, for determining the condition of the corresponding storage elements of a segment of drum 47. Each reader station controls the operation of the elements 1 through 15 of a respectively connected character module 35 in accordance with the pattern of energized storage element sensed by the reader station from the segment of the drum passing opposite it.

The reader station of FIG. 7 is modular designed so that additional reader drums 47 may be added readily to increase the display capacity of the reader station or to operate remote reader stations. To accomplish this a circuit 280 is used to produce write signals for the next drum. Circuit 280 is actuated in response to the erase signals on line 276 used to extinguish a lamp of the preceding drum. Actuation of circuit 280 produces a write signal for the next drum. Another circuit 282 provides sync pulses directly from the output of diode 206 to the motor of the next drum. Start signals are produced by a relay K6 whose normally closed contacts are actuated by a detent 240 whose follower rides on the periphery of cam 242 which has six notches 243 spaced 60° apart. When the controls of relay K6 are closed, which occurs when the follower of detent 240 is in one of the notches 243, a continuous start pulse is produced which is applied to a circuit 281. This pulse is produced until drum 47 starts to rotate, that is, the detent is in the notch 243 for only 3 1/3° of cam rotation, after which time relay K6 opens. This removes the start signal and permits the sync pulses from diode 206 to be conveyed to the next drum. Circuits 280 and 281 correspond to transfer circuit 53 of FIG. 1.

Each additional reader unit would be of the same configuration as that shown in FIG. 7. The units may be added on or placed at remote locations quite easily since they all use the same signals and generate the proper signals for the next reader drum.

It should be understood that if two or more reader drums are used at the same location, the circuits 281 and 282 for producing start and sync signals may be dispensed with. In this case, the drums would be rotated by a common shaft, or in response to the same input signals, so they would be in synchronism at all times.

FIGURE 8 shows the circuit details of a reader drum 47, and the corresponding reader stations and controlled character modules 35. Only the components for two segments of the drum and two reader stations are shown but it should be understood that the circuit arrangement for the other four drum segments and reader stations are the same. These have been omitted to avoid duplication. It should also be understood that while a six-station system is described, a reader drum may be utilized with as many segments as desired, together with a corresponding number of reader stations and character modules 35.

Referring now to FIG. 8, the drum 47 is shown broken into 60° segments one through six, each having a respective bank of lamps. Each bank has fifteen lamps, numbered 300-1 through 300-15, which are located beneath the surface of the drum on a rotatable hub and spaced along its length. A separate slot is cut in the cover placed over the lamps inside the drum for 60° there-around for each lamp of a bank. Thus, as each lamp 300 is energized, it produces light through its own slot, this light being visible through the entire 60° of the slot. The lamps 300 in a bank are shielded from each other within the drum as are the slots, so that the light from an energized lamp shines only through its corresponding slot.

The lamps 300 of the bank of drum segment one are illustratively shown located in operative relationship with reader station one which controls character module 35-1 of word unit 30. In this position the bank of lamps of drum segment six are located in operative relationship with reader station six. As drum 47 rotates, the bank of lamps of segment one also rotates successively past the other reader stations two through five. Each reader station has a switching circuit formed by a plurality of photoconductive cells. Fifteen photoconductive cells 320-1 through 320-15 are provided and each cell is used to detect whether the correspondingly numbered lamp 300 opposite it is energized or extinguished.

Energization of the lamps 300 of the lamp banks is accomplished by signals applied over the write line 210 to the commutator 270. As can be seen, the lower end of each of the lamps 300 in a bank is connected to a common line which is in turn directly connected to a separate continuous 360° conductive ring 270a. B+ potential is applied to the commutator 270a at all times so that the lower ends of all of the lamps 300 in all of the banks have B+ thereon at all times. The upper end of each of the lamps 300 in all of the banks is returned by a respective resistor 302 to a common line and to another separate and continuous 360° conductive ring 270b which is grounded. The upper end of each of the lamps 300 is separately connected to one of the segments 270-1 through 270-108 of commutator 270. Eighteen of the commutator segments are used for each 60° segment of the drum, each commutator segment occupying approximately 3 1/3° out of the total 360° of commutator space available. The first fifteen segments of each set of eighteen are connected to respective lamps in a bank while the sixteenth, seventeenth and eighteenth segments are shorted together and used as rest or spacer segments between lamp banks.

As shown, the lamps 300-1 through 300-15 of the lamp bank of drum segment one are respectively connected to commutator segments 270-1 through 270-15. Since the character modules 35 have only fifteen elements, only fifteen information pulses are needed in the composite signal and these are considered to occupy even-numbered spaces ten through thirty-eight of FIG. 4. Thus, the last three even-numbered spaces of the composite signal and the last three commutator segments of each drum segment are not used here. If an eighteen element character module is used, or if additional information for control or other purposes is to be transmitted, then the last three even-numbered spaces and commutator segments may be used.

The last three commutator segments 270-16, 270-17

and 270-18 of the drum segment one are used as spares here and are preferably connected together and to the ground potential point on commutator 270. The same connection is made for the last three commutator segments in each drum segment one through six. As shown, the upper ends of the lamps 300-1 through 300-15 of the bank in drum segment six are respectively connected to commutator segments 270-91 through 270-105, and commutator segments 270-106, 270-107 and 270-108 are returned to commutator 270b. Similar connections to the various commutator segments (not shown) are made for the lamps 300 of the banks for drum segments two through five.

As shown, the brush at the end of write line 219 is in contact with commutator segment 270-1. The position of the brush advances from segment 270-1 through segments 270-18 as the motor is stepped around through a 60° rotation. This stepping of the brush continues for segments 270-1 through 270-108 as drum 47 is rotated 360°. When a write (information) signal is present on write line 210 the lamp 300 electrically connected to the line through its commutator segment is illuminated, thereby storing the information pulse from the composite signal of FIGURE 4. As should be clear, energization of the various lamps 300-1 to 300-15 of a bank is accomplished in time correspondence with the occurrence of the original information signals at the corresponding places of the composite signals. This ensures that the correct element of a character module 35 will be illuminated to produce the desired character.

A lamp 300 is energized by the presence of a negative going information signal on line 210 which is applied to the upper end of the connected lamp. Since the lower end of the lamp has a positive potential applied thereto, a sufficiently high potential difference is produced across the lamp to ionize its gas so that it becomes energized and emits light. When the drum steps the brush of line 210 over to the next commutator segment, the lamp energized previously remains energized since the B+ potential applied thereto by conductive ring 270a is sufficiently high to maintain it in the energized condition. However, the B+ potential from ring 270a is not sufficient to energize a lamp 300 by itself.

As can be seen, depending upon the original information signals in the composite signal of any character frame, one or more of the lamps 300-1 through 300-15 of a bank are energized successively. Thus, a pattern of energized lamps is produced on each drum segment by the signal of each character frame corresponding to the information needed to visually reproduce one character on a module 35. The lamps for all six drum segments are controlled in the same manner.

As each bank of lamps 300 of a drum segment pass by a reader station, the elements of the character module 35 controlled by that reader station are illuminated in accordance with the energization of pattern of the lamps in the bank. Each reader station has a switch 30 formed by a number of photoconductive cells 320 corresponding to the number of lamps 300 in each bank. Photoconductive cell 320-1 is located opposite the slot in the drum 47 through which the light from lamp 300-1 of a bank would emanate and the other cells are located in like manner opposite the slots of the correspondingly numbered lamps. It should be understood that a photoconductive cell 320 can only receive the light from the correspondingly numbered lamp 300 and both the lamps and the cells are suitably shielded to ensure that this occurs.

The photoconductive cells 320-1 through 320-15 of reader stations one respectively have their upper ends connected to a correspondingly numbered one of the elements 1 through 15 of character module 351-1. The other end of each of the photoconductive cells 320 of reader station one is connected to one side of a suitable source of potential, such as an alternating current potential source,

as are the lower ends of all the elements 1 through 15 of character module 351-1. On sensing light from a corresponding lamp 300 opposite it, each photoconductive cell has its high dark resistance lowered, permitting AC voltage to be applied across the corresponding electrically connected element of the character module and causing the element to become illuminated. Therefore, by energizing selected lamps 300 of drum segment one, selected elements of character module 351-1 are energized to visually produce the desired character.

Once the lamps 300 of drum segment one are selectively energized, they stay energized until some step is taken to extinguish them. This is not done until drum segment one has rotated a full 360°. Thus, the lamps 300 of drum segment one rotate past the photoconductive cells 320 of reader stations two through five (not shown) and six and cause the same character to be visually produced on the character module operated by the reader station.

After the lamps of drum segment one have passed by the brush of line 210, i.e. the brush is on commutator segment 270-19, the lamps of drum segment two (not shown) are selectively energized in the same manner as previously described by the information signals of the next character frame. Drum segment two successively passes by reader stations one through six and character modules 351 through 356 are illuminated to produce the character represented by the information stored in the lamps of drum segment two. This process continues successively for each drum segment so that information corresponding to six characters can be stored by the drum and the six characters modules 35 controlled by the six reader stations operated at one time to visually produce the six characters.

After the information stored in the lamps of a drum segment has operated all six character modules of a word unit, i.e., the drum has rotated 360° and the same character has been successively produced on each of the six modules, an erase operation is performed to permit new information to be written into the lamps of the drum segment. As seen in FIGURE 8, the brush at the end of erase line 276 is located one commutator segment ahead of the brush for write line 210. In the drum position illustrated, lamp 300-1 is connected through commutator segment 270-1 to the write line 210, so that it may be energized if the appropriate write signal appears. At the same time, commutator segment 270-2, which is fixedly connected to lamp 300-2, is in contact with the brush for erase line 276. Thus, lamp 300-2 may be extinguished if it was energized 360° previously, and new information written into it as the commutator advances one more step to put commutator segment 270-2 in contact with write line 210. This successive erasing and writing continues for each lamp so that for each 60° rotation of drum 47, corresponding to one character, all of the lamps in the segment of the drum first have the stored information erased and then new information written in. The same erasing-writing operation is carried out for the lamps of the other five drum segments as their respective commutator segments pass by the brushes for the write and erase lines. The production of the erase signals and their use to transfer the information signals to other drums is described below.

FIGURES 9A and 9B taken together show circuit details for most of the blocks of the diagram of FIGURE 7.

Since the majority of the circuits used are conventional, many details with respect to the biasing and coupling circuits are omitted from the following description. It is sufficient to say that the plus (+) and minus (-) signs shown adjacent various components of the circuit correspond to positive and negative supply potentials for the transistors. Also, while transistors of one conductivity type are described (NPN or PNP), it should be obvious that the opposite conductivity type can be used in some cases upon proper change of the biasing potentials and/or

input signal polarities. This is well within the knowledge of one skilled in the art.

The negative going start pulses at terminal 201 are applied through diode 201 to the base input of a PNP transistor 402 connected in emitter-follower configuration.

Negative going output pulses appear across the emitter load resistor 403 and are coupled through a network 404 to the base of a common-emitter connected NPN transistor 406. The output signal at the collector of transistor 406 is opposite in polarity to the input signal and these positive going pulses are directly applied to the base of another PNP emitter follower stage 408. The negative going start pulses at input terminal 201 appear across the emitter resistor 409 of transistor 408 as positive going pulses and these positive pulses are coupled through a diode 410 to charge a capacitor 412. Capacitor 412 is part of a peak-detector circuit. When it charges to a sufficiently high voltage, corresponding to the receipt of the proper number of start pulses from terminal 201 in succession or a continuous pulse, a sufficiently high amplitude voltage is applied to the base of an NPN emitter-follower transistor 414 to overcome its bias and to render the transistor conductive. The positive voltage accumulated across capacitor 412 in response to the start pulses appears as a positive going pulse across the emitter-resistor 415 of transistor 414. This positive going pulse is applied to the base of an NPN emitter-follower amplifying stage formed by a transistor 416 which drives a direct connected PNP transistor amplifier 418 connected in common emitter configuration. The negative going output at the collector of transistor 418 drives a PNP power transistor 420 also connected in common emitter configuration whose collector is connected directly to the coil of relay K4.

Appearance of the positive going pulse across the emitter load resistor 415 of transistor 414, corresponding to detection of the start pulses causes transistor 420 to conduct. This energizes relay K4 lifting detent 220 out of the notch 223 of cam 222. When this occurs the contacts of relay K4 are closed applying power (B+) to the collector of a common emitter connected NPN transistor 430. Transistor 430 is connected in series with terminal 200 and the ring counter 250 for the motor drive circuit. The base of transistor 430 receives positive sync pulses from terminal 200 through diode 206 and a PNP emitter-follower transistor 432. As explained before, each sync pulse causes the motor 48 to advance one step and produce a $3\frac{1}{3}$ ° rotation of the drum 47 in the system under consideration. Until relay K4 is energized, by detection of the start pulses, detent 220 prevents rotation of the drum 47. However, once relay K4 is energized, the follower detent 220 is lifted out of the notch 223 and the motor drive circuit is energized to respond to the sync pulses.

The details of the ring counter 250 for the motor drive circuit are not shown since they are well known in the art and no further description thereof is needed. It should be understood that any suitable drive circuit may be used instead of the ring counter, for example, a number of multivibrators which are alternately triggered on and off by the sync pulses in a manner to produce the necessary input pulses to operate the preferred Slo-Syn motor. It also should be understood that any other suitable type stepping motor may be utilized and the drive circuits therefor would be selected accordingly. Many such motors and drive circuits are commercially available.

When no start pulses are detected, the follower of detent 220 is left in a notch 223 and the drum 47 is kept from rotating. The time constant circuit of capacitor 412 and resistor 413 for the detector are selected to prevent energization of relay K4 except in response to the proper number of successive start pulses or the continuous pulse.

The normally closed contacts of relay K5, which are connected between the B+ bias source and the collector of transistor 406 in the start pulse detector circuit, are

opened after approximately 10° of rotation of the reader drum 47 during each character frame. This de-energizes the remainder of the detector circuit and there is no output from transistor 420. While this removes current from the coil of relay K4, the contacts of this relay remain closed since the follower of detent 220 rides on the raised periphery portion of cam 222. The opening of relay K5 can be selected as desired.

The information signals, which are also negative, are applied through diode 205 and emitter-follower transistor 402 to the base of a common emitter connected NPN transistor 440. The negative going information signals appear as positive going signals at the collector of this transistor and they are applied to the base input of a common emitter NPN amplifying transistor 442. The collector of transistor 442 is connected to a B+ potential source (not shown) of greater magnitude than the other biasing potentials and therefore shown by the two plus (++) signs. The output of transistor 442, in response to an information pulse at terminal 201, is a large amplitude negative pulse and this is coupled through a capacitor 444 onto the write line 210. A diode 446 is connected between the output side of capacitor 444 and ground to eliminate any positive overshoots during production of the write pulses.

A negative write pulse is produced in line 210 in response to each information pulse at terminal 201. Line 210 is connected to a segment of commutator 207 and then to the lamp 300 which is to have the information signal written therein. A negative write pulse on line 210 causes the connected lamp 300 to be energized. Since one side of the lamp is always connected to B+ potential through commutator ring 270a, when the other side of the lamp receives the negative write pulse on line 210 a sufficiently large potential difference is produced to energize the lamp. Once the negative pulse is removed from line 210, the energized lamp stays on since the B+ potential from commutator ring 270a is sufficient to maintain the lamp energized.

As explained previously, an erase circuit 275 is provided to extinguish each energized lamp 300 after it has completed a 360° rotation with drum 47. The erase circuit includes an NPN voltage level sensing transistor 450 connected in common emitter configuration and having its base directly connected to the erase line 276. Considering for a moment that there is no erase pulse present on line 276, the input to transistor 450 senses whether or not the lamp 300 connected through its respective commutator segment 270 to the brush for line 276 is energized or extinguished. By referring to FIGURE 8, it can be seen that when a lamp is off, there is no voltage drop across the connected resistor 302, one end of which is connected to the grounded commutator 270a, since no current is flowing through the lamp. However, if a lamp is energized, then current flows through the lamp and a positive voltage drop appears across resistor 302. This voltage is also present on line 276. The value of the resistors 302 is selected to produce any desired magnitude voltage drop and the transistor 450 can be made to conduct in response to this magnitude voltage, or one very close thereto, by adjusting its base to emitter bias.

Considering that the lamp 300 whose commutator segment is making electrical contact with line 276 is energized, the positive voltage drop across the connected resistor 302 makes transistor 450 conduct. A negative going signal is produced at its collector which is coupled through capacitor 452 and diode 454 to the base of the left-hand NPN transistor 456 of a cross-coupled bistable multivibrator whose right-hand section is an NPN transistor 458 of the same type. Considering that the multivibrator is in a "rest" condition with transistor 456 "on" (conductive) and transistor 458 "off" (non-conductive) a negative going pulse is present at the collector of transistor 450 which is coupled directly to the base of transistor 456, causing the multivibrator to switch state. The rest condi-

tion is produced in response to each sync pulse which is applied to the base of a common emitter NPN reset trigger transistor 449 through a capacitor 448. The collector of transistor 449 goes to zero in response to a sync pulse, and the negative going output is applied directly to the base of NPN transistor 458 turning it off and transistor 456 on.

When the multivibrator switches state from the rest condition, transistor 465 becomes non-conductive, thereby producing a positive pulse at its collector electrode, and transistor 458 conductive, thereby producing a negative going pulse at its collector electrode. This negative going pulse is coupled to the base of an NPN transistor 460 connected in common emitter configuration to render this transistor non-conductive. This produces a positive going pulse at the collector of transistor 460 which, when coupled to the base of an emitter follower NPN transistor 462, turns this transistor on producing a high positive voltage pulse across its emitter load resistor 463. This pulse is coupled through a diode 464 onto the erase line 276 and applied to the end of the lamp 300 in contact with the erase line 276 through its commutator segment 270. The positive voltage on line 276 applied to one side of the lamp taken with the positive voltage applied to the other side of the lamp continuously through the commutator ring 270a produces a voltage drop or difference of substantially zero across the lamp, thereby extinguishing it.

When no voltage is developed across a resistor 302, meaning that the corresponding lamp 300 is off, there is no negative pulse coupled to the base of transistor 456 of the multivibrator. Thus, transistor 456 stays on and transistor 458 off. The collector of transistor 458 remains at a high positive potential turning on transistor 460, thereby dropping the voltage and its collector and in turn making transistor 462 non-conductive. In this case no voltage is developed across the emitter load resistor 463 and no erase pulse is produced on line 276.

As explained previously, it is possible to increase the capacity of the system by using additional reader drums 47 and character modules 35. The circuits for producing the signals to control the additional drums are shown in FIGURE 9B. Considering first the production of the start pulse for the next drum, detent 240 holds relay K6 closed between the time that the motor 48 driving drum 47 is first energized and its first step. Thus, the contacts of relay K6 are closed for the first $3\frac{1}{2}$ ° rotation of the drum. During this time, as seen in FIG. 9B, the closed contacts apply B+ through a diode 480 to the base of a common emitter PNP transistor 482. This positive voltage turns off transistor 482 causing its collector voltage to become more negative and thereby causing a series connected emitter follower PNP transistor 484 to become conductive and produce a negative going pulse across its emitter load resistor 485. This pulse is fed onto line 487. This is the start pulse for the next unit which is produced continually until the time motor 47 has gone one step. No detector is needed at the second reader unit to detect the start pulse on line 487 and it can be used to drive a relay amplifier directly for relay K4 of the next reader unit.

To transfer the write pulses of the drum segment being erased to the next drum, a connection is made to line 276, on which the positive erase pulses from transistor 462 appear, through a Zener diode 490 to the base of a common emitter NPN transistor 492. Zener diode 490 is selected to pass pulses only of a magnitude corresponding to the erase pulses. As explained previously, an erase pulse is produced only when one of the lamps 300 is sensed as being on, the lamp being originally placed in this condition by the receipt of an information pulse. It should also be noted that no erase pulses are produced until after relay K6 has been opened.

The positive going erase pulses, which correspond to information pulses written in the lamps being erased,

cause the collector voltage of transistor 492 to drop and produce a negative going pulse. This pulse is coupled through a capacitor 493 and a resistor 494 onto line 495 and to the next reader unit. It should be clear that a negative going pulse is produced on line 495 each time an energized lamp is sensed in drum 47. Thus, the exact pattern of information pulses written into drum 47 is reproduced on line 495 at the same time spaces of a character frame after an erase pulse as the original pattern produced by data source 40. This permits the information corresponding to one character to be transferred to another reader unit, after the information has been used to sequentially control all six character modules of the first unit.

The sync pulses for the next reader unit are produced by directly coupling the positive going sync pulses at the output of transistor 432 to the next reader unit sync pulse input line. An amplifier may be provided for the sync pulse input at the next reader unit, if desired.

The circuitry for the next reader unit, and all others, would be the same as that shown in FIGURES 9A and 9B, with the exception of the circuitry omitted since all of the signals for the next unit are the same as the signals for the preceding unit. As pointed out above, no start pulse detector is needed for the second reader unit. Therefore the start pulse would be coupled directly to the relay amplifier 416, 418 providing inverting stages if needed while the negative information pulses would be applied directly to the input transistor 440 of the write amplifier. Also, the drum 47 for each other reader unit is of the same construction as the drums of FIG. 8. Therefore, as can readily be seen, the modularized construction of the reader unit of FIGS. 8, 9A and 9B permits the character capacity of the system to be increased quite easily to two, three or more units.

When two or more reader units are to be used at the same location, it is not absolutely necessary to provide the circuits for producing the negative start pulses and the positive sync pulses on lines 487 and 508. In this case all that need be done is to place all of the reader drums 47 on a common shaft. In this event, all of the drums are rotated in synchronism.

The construction of the circuits of FIG. 9B for producing the signals for application to the next drum also gives the system the capability of operating remote reader units. In this event it is only necessary to couple the signals appearing on lines 487, 495 and 508 to a remote unit by any suitable transmission medium such as a transmission line, radio or microwave link, etc. The remote reader unit is of the same construction as that previously described and operates in the same manner.

FIGURE 9C illustrates how data is transferred serially from one drum unit 47-1 to the next drum 47-2. Here, drum 47-1 has completed one full revolution of 360° so that the brush from write line 210 is in contact with commutator segment 270-108 while the brush from erase and transfer line 276, located one step in advance, is already in contact with segment 270-1 to erase old information. The data in the lamp 300 whose respective commutator segment is in contact with the brush for the erase line is applied to a regenerative amplifier 498. Amplifier 498 comprises the voltage level sensing transistor 450, the bistable multivibrator 456 and 458, erase pulse amplifiers 460 and 462, multivibrator reset transistor 450, the write information transfer amplifier 492 and the associated circuit components therefore as shown in FIG. 9B, that is, all of FIG. 9B except relay K6 and transistors 482 and 484 which are used to produce the start pulse for the next drum.

As explained above the write information transfer amplifier 492 of the regenerative amplifier 498 produces an output pulse on line 495 each time the sense and erase line 276 comes into contact with a commutator segment whose connected lamp is on.

This information transfer pulse is applied to the seg-

mented commutator 270 for the next drum 47-2. Drum 47-2 is similar in construction and operation to drum 47-1, except that it receives its information signals from line 495 and the regenerative amplifier rather than from the composite signal. A positive pulse on line 495 to the commutator for drum 47-2 is applied to one side of the lamp connected to the commutator segment receiving the pulse. This positive pulse turns the lamp on since, when taken in combination with the B+ voltage applied continuously to the other side of the lamp, exceeds the lamp striking voltage. Suitable driving amplifiers may be provided at the commutator write input for drum 47-2 if needed, to increase the amplitude of the positive pulse.

The brush for write line 495 for drum 47-2 is located at the same place with respect to this drum as is the brush from erase line 276 of drum 47-1. Thus, for example, as data is being erased from the lamp connected to commutator segment 270-1 of drum 47-1 (drums advanced one step from that shown in FIG. 9B), information is written into the corresponding lamp connected to commutator segment 270-1 of drum 47-2. In a like manner, information from the lamps of drum 47-1 is transferred in serial sequence to the corresponding lamps of drum 47-2 as both drums rotate synchronously. Thus, the lamps of drum 47-2 are energized serially in the same pattern as the lamps of drum 47-1 so that the same letters previously displayed on character modules 35-1 through 35-6 are transferred to character modules 35-7 through 35-12. Of course, the actual transfer of data between two units is from the last module of one unit to the first module of the next, for example from module 35-6 to module 35-7. The circuit for producing the start pulse for drum 47-2 was described previously.

If desired, a third and additional reader units may be provided. This would entail using the erase line 276 of drum 47-2 to drive another regenerative amplifier 498 which would in turn produce write signals for the commutator of a third drum 47-3 and associated character modules 35-13 through 35-18 (not shown). Also, each unit would be provided with the necessary circuits to produce the start pulse for the next unit, if the drums are not driven on a common shaft. The capacity of the display system may be extended as needed simply by adding on the modularized reader units.

The reader unit described in FIGS. 7-9 operates in the desired manner to display a character in accordance with the composite signal supplied by source 40. However, when displaying a character on the first module 35-1 of the first word unit (and the first module of the word unit for each other reader unit), the character is actually "assembled" there, since it takes almost a 60° rotation of the drum 47 before commutator segments 270-1 through 270-15 contact write line 210 and all fifteen elements of module 35-1 are able to be energized. A viewer of the word unit 30-1 would see the individual elements of module 35-1 becoming energized to produce a character and then this character next appearing complete on module 35-2 at the beginning of the next character frame time, that is when the lamp bank of drum segment originally opposite reader station one moves into operative position with the cell bank of reader station two. The character appears complete at all times on modules 35-3 through 35-5, and at the beginning of the last module 35-6 of a word unit. However, on module 35-6 it is erased, or "torn down," an element at a time by the commutator segments of the lamp bank sequentially coming into contact with the erase line after the drum has rotated 360°. Thus, the character on module 35-6 disappears an element at a time, either by erasing or transfer to the next reader unit. The character is also "built up" a segment at a time on the first module of the next reader unit and destroyed an element at a time on the last module of that unit.

While the sequential "assembling" and "tearing down" of a character is not objectional in most cases, FIGURES

10A, 10B and 10C show another type of reader unit for preventing this. Here, the serially occurring information for a character is assembled in a storage medium external of the reader drum of the first reader unit and read into the drum in parallel so that the character initially appears complete at the first step of the drum into operative position with the cell bank of the reader station controlling the first character module. Also, an arrangement is provided for erasing the information in parallel after the last character module of a word unit has displayed the complete character for a full 60° rotation of the drum and/or transferring it in parallel to the next drum. A substantial portion of the circuitry of the reader unit of FIGS. 9A and 9B is utilized in the system of FIGS. 10A-10C as will be described. Therefore, the detailed circuits of FIGS. 9A and 9B are not repeated.

The external storage register includes a shift circuit 600 operated in response to the sync pulses. The shift circuit sequentially conditions the storage elements of a register 610 which are written out in parallel by a commutator 620 into a bank of lamps 630 in a drum 647 prior to this bank coming into operative relationship with reader station one. As the drum 647 rotates, the bank of lamps energized by the external storage register first comes opposite the photoconductive cells of reader station one and character module 35-1 is energized immediately. The bank of lamps then is rotated past the other five reader stations and on the eighteenth step of opposite reader station six, the information on the bank of lamps is erased in parallel by a set of regenerative amplifiers. If desired, this information may be transferred in parallel to a second drum and the character capacity of the system extended in a manner similar to that previously described.

Considering the shift circuit 600 in detail, eighteen glow lamps 601-0 to 601-17 are provided. The upper end of each odd numbered lamp 601-1 to 601-17 is connected through a correspondingly numbered resistor 602 to a common line 603 which is in turn connected to the B+ source by a resistor 604a. The upper end of each even numbered lamp 601-0 through 601-16 is connected to line 603 through a respective correspondingly numbered diode 604 which is poled to pass B+ voltage from line 603 to the lamp. A capacitor 605 connects the lower end of an even numbered lamp to the lower end of the next higher odd numbered lamp while another capacitor 606 is connected between the upper end of each odd numbered lamp and the upper end of the next higher even numbered lamp. A diode 607 connects the lower end of each odd numbered lamp to a common line 609 while a resistor 608 connects the lower end of each even numbered lamp to this line.

Line 609 is connected to the center movable arm of a single pole double throw relay 593 whose stationary contacts are connected to ground. The center arm of relay 593 is operated by detent 220 which rides on the periphery of the drum (FIG. 10C) and falls into notches spaced every 60° therearound. The left contact of relay 493 is normally closed when detent 594 is in a notch. Relay 593 is another set of contacts on relay K4 of FIGS. 9A-9B.

The positive sync pulses at the emitter resistor of transistor 432 (FIG. 9A) are applied through a diode 595 onto line 596 and through an RC coupling network to the base of an NPN transistor switch 597. A capacitor connects the collector of this transistor 597 to line 603 at the right hand side of resistor 604 while voltage divider formed by resistors 599a and 599b is connected between B+ and ground, with the junction of these two resistors also connected directly to the collector.

When the reader drum 647 is in the rest position and detent 220 is in one of the notches 223 on a cam 222, or on the surface of the drum, lamp 601-0 is turned on by the B+ voltage applied through resistor 604a and diode 604-0. Lamp 601-0 is the pilot lamp. The lower end of lamp 601-0 is connected to ground through resistor 608-0 so it has a complete path for conduction. The lower ends

of all the other lamps are ungrounded at this time since the movable arm of relay 593 is in the position shown and, therefore, these lamps cannot be turned on.

After the four start pulses have been received, relay K4 picks up and closes the right hand contact of relay 593 thereby grounding the components 607 and 608 connected to the lower ends of lamps 601-1 through 601-17. Relay K4 stays closed by the detent 220 riding on the drum periphery for 60° and this permits the other lamps to be energized sequentially during the remainder of the frame time. The first sync pulse coming in over line 596 is applied to the base of NPN transistor switch 597 causing it to saturate quickly. This discharges capacitor 598 and drops the potential at the right hand side of resistor 604a by an amount equal to the original potential at the junction of the two resistors 599a and 599b. This causes lamp 601-0 to turn off since the voltage at the upper end of capacitor 598 is now less than that needed to maintain lamp 601-0 on.

While transistor 597 is still saturated, the upper end of capacitor 598 charges through resistor 604a toward the B+ potential, this potential appearing at the end of resistor 602-1 connected to line 603. At the same time the negative voltage at the right hand side of capacitor 605-0 is applied to the lower end of lamp 601-1 and the combined positive and negative voltages across this lamp on line 603 and from the capacitor 605-0 turns on lamp 601-1. The negative voltage at the right hand side of capacitor 605-0 is produced by the capacitor charging through resistor 608-0 when lamp 601-0 is on. Since this negative voltage cannot be passed by oppositely poled diode 607-1, it appears at the lower end of lamp 601-1. Lamps 601-2 through 601-17 cannot be ignited in response to the first sync pulse since their respectively connected input capacitors 605 and 606, one number lower than the number of the lamp, are not charged.

Lamp 601-1 stays on until the next (second) sync pulse is received. This pulse again drives transistor 597 into saturation thereby discharging capacitor 598 and dropping the positive voltage on line 603 to turn off lamp 601-1. When capacitor 598 starts to charge toward B+, the voltage on line 603 and applied through diode 604-2 to the upper end of lamp 601-2 is aided by the positive voltage on the right hand end of capacitor 606-1 to turn on lamp 601-2. This capacitor is charged during the time lamp 601-1 is on through diode 604-2 and resistor 602-1. Lamp 601-2 stays on until the next sync pulse is received and during its on time it charges capacitor 605-2 with a positive voltage at its right hand end to aid in striking lamp 601-3.

The operation of the shift circuit 600 in sequentially turning on lamps 601-3 through 601-17 in response to the third through seventeenth successive sync pulses continues in the manner previously described. The eighteenth sync pulse turns off lamp 601-17 and since the detent 220 falls into the notch at that time, pilot lamp 601-0 is turned on again awaiting the next train of sync pulses. Reference is made to an article by Manley and Buckley in the January 1950 edition of Electronics for a more complete description of the shift circuit.

Located opposite each of the lamps 601-1 through 601-15 is a correspondingly numbered photoconductive cell 611-1 through 611-15. There are no cells opposite lamps 601-16 and 601-17 since these are not used for information purposes. Each time a cell 611 senses light from a corresponding lamp 601, its resistance decreases and it connects the left terminal of a respectively connected signal storage capacitor 613 to a signal line on which negative write pulses from write line 210 appear. The right hand terminal of each capacitor is connected to ground. Each time one of the cells 611 conducts, its connected capacitor 613 is charged with a negative voltage on its left hand terminal when a pulse appears on line 210 through diode 614. Since the cells 611-1 through 611-15 are successively rendered conductive by the lamps 601-1

through 601-15 of the shift circuit, in response to the successively occurring sync signals, a pattern of information signals can be written into the corresponding capacitors 613-1 through 613-15. This pattern corresponds to the pattern of information signals on write line 210. Therefore, the serially occurring information signals are stored in the capacitors 613 from which they can be written into the drum 647 in parallel through a set of write brushes 617 numbered corresponding to the capacitors. It should be recalled that for each period of the character frame time that a sync pulse occurs first (odd numbered spaces) and then an information pulse (even numbered spaces) if one is to be produced. The sync pulse conditions each capacitor to be charged by a negative information pulse on line 210. Each capacitor stays conditioned only until the next sync pulse is received.

The drum 647 (FIGS. 10B and 10C) is similar to drum 47, in that it has six banks of lamps, each bank spaced 60° apart and occupying a small angular segment. There are 60° slots in the drum adjacent each lamp in a bank so that the light produced thereby is visible for 60° rotation of the drum. As before, suitable shields are provided so that one lamp energizes only one photoconductive cell. Also, the drum 647 is provided with the various timing cams 222, 232 and 242, only cam 222 being shown.

Each bank of lamps has a set of commutator segments 620-1 through 620-15 which are separate and located spaced 60° apart on drum 647 or its shaft. Each commutator segment of a set is connected to one of the lamps in the respective bank which it controls. As shown in FIG. 10C, each 60° drum segment has its set of commutator segments 620 located at approximately the angular mid-point thereof and aligned with one of the notches 223 for the start relay. The write brushes 617 are located near reader station one to write new information into a lamp bank after it has passed by reader station six.

With the drum in the rest position, that is detent 220 in a notch 223, the set of write brushes 617 from the storage capacitors 613 contact all of the segments of the commutator set under it and write information into the lamp bank. The cells of the reader stations are advanced 30° with respect to the notches 223 and commutator sets 620 in the drum rest position so that the bank of lamps being energized by the write brushes 617 will produce a pattern which will be sensed by the cells of reader station one and energize character module 35-1. The other modules 35-2 through 35-6 will be illuminated even when drum 647 is stationary, due to the 30° advance of the reader stations. When the drum is in its rest position the message does not move.

Only one bank of lamps 630 is shown in detail (FIG. 10B) for the drum, but the other five lamp banks are identical. The lower end of each lamp 630 is connected through a respective correspondingly numbered resistor 632 to a ground point brought into the drum through a 360° commutator ring 650 while the upper end of each lamp is directly connected to a line 651 connected to a B+ potential source brought into the drum through a 360° commutator ring 652. The B+ voltage is sufficient to keep a lamp 630 on once it is fired, but it is not sufficient to fire the lamp.

A connection is made between the lower end of each lamp 630 and a corresponding commutator segment 620 of its set. The signals applied to the lamps through these commutator segments are used to control turning on and off the lamps.

A set of stationary erase brushes 642 are located adjacent the write brushes 617. Erase brushes 642 are advanced by one step (3½°) with respect to the write brushes 617. Therefore, the commutator segments 620 of each lamp bank make contact with erase brushes 642 one step earlier (3½°). The set of commutator segments and the brushes 617 and 642 are arranged so that the erase brushes contact a set of commutators at the seven-

teenth step of a drum segment lamp bank past reader station six and to contact the write brushes 617 at the eighteenth step. At the eighteenth step the detent 220 rests in a notch 223 and the drum is at rest. As should be clear, the commutator set for each lamp bank of the drum sequentially comes into contact with brushes 642 and 617 so that the old information in a bank is first erased or transferred by brushes 642 and new information is written into a lamp bank by brushes 617 to be held for 360° rotation of the drum past reader station six.

When the brushes 617 contact the commutator segments, the voltage stored in a corresponding capacitor 613 is applied through a brush 617 and a commutator segment 620 directly to the lower end of the connected lamp. Since the voltage is negative at the left hand side of a capacitor 613, a sufficiently high voltage difference is produced across the lamp to cause it to fire. If desired, an amplifier may be placed between each capacitor 613 and its respective commutator segment 620 to increase the magnitude of the positive voltage pulse applied to the lower end of each lamp.

It should be understood that register 610 is external to the drum and converts the serially occurring information pulses of the composite signal into a stored pattern which can be read out in parallel written into a lamp bank prior to the time that the bank makes its first step into operative relationship with reader station one for module 35-1. Therefore, the character is displayed immediately and completely at the first step and, in fact, is displayed with the drum in rest position.

As the drum 647 rotates for each 60°, the serially occurring information signals in the current character frame are converted into the parallel stored signals by the shift circuit in the manner previously described. These signals are then written into the drum in parallel at the eighteenth sync pulse of the character frame. Thus, there is almost a one frame delay between receipt of the first information signal and the time that the complete frame of information signals is written into a lamp bank in parallel.

After a lamp bank whose lamps have been energized in a predetermined pattern has rotated past the first five reader stations and for 16 steps past reader station six, brushes 642 come into contact with the set of commutator segments 620 for the bank at the seventeenth step of the motor. Connected to each of the brushes 642 is a regenerative amplifier circuit 497 which is the same as the circuit previously described with respect to FIG. 9B. The circuit details are shown in FIG. 9B. As previously described, the regenerative amplifier circuit senses the presence of a lamp being on, produces an erase pulse to extinguish the lamp, and also produces an information pulse for transfer to another reader drum, if desired. Fifteen regenerative amplifiers are provided, one for each commutator segment 620 and brush 642, so that all fifteen lamps in a bank are erased at the same time and write signals produced in parallel for transfer to the next reader drum. The transfer operation is described in greater detail in FIG. 12.

FIG. 11 is a block diagram of a reader unit in which information is written into drum 647 in parallel. Many parts of this unit are the same as previously described with respect to FIGS. 7-9 so that the same reference numerals are utilized and no further detailed description thereof is given.

The composite input signal, with the serially occurring information pulses, is used to energize relay K4 and drive the ring counter 250 and motor 48 in the manner previously described. The information pulses at the output of write amplifier 209 are applied to the serial to parallel converter described in FIG. 10A and the 15 output lines of the converter which appear at brushes 617-1 through 617-15 are located adjacent the sets of commutator segments 620 of the drum to make contact therewith as each bank of lamps approaches reader station one. Also, 75

as described with respect to FIGS. 10A-10C, the erase brushes 642-1 through 642-15 are located adjacent drum 647 to contact a set of commutator segments 620 one step in advance of write brushes 617. These brushes 642 supply respective regenerative amplifiers 497 so that the same pattern of output signals is present on these amplifiers as was detected by the erase brushes. This pattern of signals on the output lines of the regenerative amplifiers 497 supplies information in parallel to the next drum.

Drum 647 is also provided with cams 222, 232 and 242 whose functions have been previously described. Relay K4 has the extra set of contacts 593 (FIG. 10A) which are used to open the circuit to ground for line 609 thereby disabling lamps 601-1 through 601-17 of the shift circuit until relay K4 has been energized. As before, sync signals are applied directly to the next drum after suitable amplification and isolation.

FIG. 12 shows the transfer of information from one drum to the next when the parallel writing system of FIGS. 10 and 11 is used. Here, information from the serial to parallel converter is written onto drum 647-1 on the eighteenth step of a 60° rotation. On the seventeenth step the old information is erased and signals corresponding thereto are produced on the output lines 20 of the fifteen regenerative amplifiers 497. These lines supply the write brushes 617 of a second drum 647-2 which is of the same construction as drum 647-1. However, the set of commutator segments for each lamp bank, or the erase and write brushes are advanced by one step.

Thus, old information on drum 647-2 is erased on the sixteenth step past reader station six and new information written in at the seventeenth step, the same time as it is erased from drum 647-1.

The parallel transfer arrangement may be carried out 35 for additional drums 647-3 . . . 647-n with one step of the information display past reader station six being lost for each additional drum. If desired storage elements may be placed in the transfer lines to hold the transferred information for one step so that, for example, information 40 is erased from drum 647-1 on step seventeen and stored in the storage elements until step eighteen at which time it is written into drum 647-2. The storage elements may be capacitors, glow lamps, etc.

As can be seen, only one shift register is needed for the 45 initial serial to parallel conversion and as many reader units as desired can be connected together with data transfer taking place from the erase brushes 642 of one drum to the write brushes 617 of the next drum.

While the lamps of the various data sources and reader 50 drums have been described as being turned on in response to signal input pulse, it should be understood that they can also be turned off in response to these pulses upon suitable modification of the lamp biasing circuits, sensing circuits and control circuits.

While preferred embodiments of the invention have 55 been described above it will be understood that these embodiments are illustrative only and the invention is to be limited solely by the appended claims.

What is claimed is:

1. A display system comprising:
a plurality of segmented modules for displaying characters by energizing selected segments,
a storage device including at least one bank of light sources, each light source of a bank when in a first condition corresponds to a segment of a character module to be energized,
means for selectively switching into said first condition certain of said light sources in a bank corresponding to the character to be displayed,
means for each display module for detecting said first condition of the light sources in a bank and for controlling the energization of the segments of the associated module in accordance therewith,
and means for scanning each bank of light sources by the detecting and control means for each module

to display the character corresponding to the detected first condition of the various light sources in a bank on each module.

2. A display system responsive to a serial sequence of information signals comprising:

a plurality of segmented modules for displaying characters by energizing selected segments thereof, a storage device including a plurality of banks of light sources, each light source of a bank when in a first condition corresponds to a segment of a character module to be energized,

means responsive to a serial sequence of signals in a predetermined pattern for selectively switching into said first condition certain of said light sources of one bank corresponding to the character to be displayed,

means for each display module for detecting said first condition of the lamps in a bank in operative relationship with it and for controlling the energization of the segments of the associated module in accordance therewith,

and means for scanning said one bank of light sources by the detecting and control means for each module so that the character corresponding to the detected first condition of said one bank of light sources is displayed on each module, and means responsive to an information signal for bringing another bank of light sources into operative relationship with the selective switching means.

3. A display system responsive to a serial sequence of information signals comprising:

a plurality of segmented modules for displaying characters by energizing selected segments thereof, a storage device including a plurality of banks of light sources, each light source of a bank when in a first condition corresponds to a segment of a character module to be energized,

register means for receiving a serial sequence of signals in a predetermined pattern and for producing a parallel readout thereof,

means responsive to the parallel readout signals of said register means for selectively switching into said first condition certain of said light sources of one bank corresponding to the character to be displayed,

means for each display module for detecting said first condition of the light sources in a bank in operative relationship with it and for controlling the energization of the segments of the associated module in accordance therewith,

and means for scanning said one bank of light sources and the detecting and control means for each module relative to each other so that the character corresponding to the detected first condition of said one bank of light sources is displayed on each module, said scanning means also bringing another bank of light sources into operative relationship with the selected switching means to receive a parallel readout of another predetermined pattern of signals corresponding to another character to be displayed.

4. A display system comprising:

a plurality of display units, each unit including a plurality of segmented modules for displaying characters by energizing selected segments thereof,

a storage device for each display unit, each storage device including at least one bank of light sources, each light source of a bank when in a first condition corresponds to a segment of a character module to be energized,

means for selectively placing certain of said light sources in a bank of light sources in said first condition corresponding to the character to be displayed,

means for each display module for detecting said first condition of the light sources in a bank in operative relationship with it and for controlling the energiza-

tion of the segments of the associated module in accordance therewith,

means for scanning each bank of light sources by the detecting and control means for each module thereby causing the character corresponding to the detected first condition of the light sources in a bank to be displayed on each module,

and means connected between the storage devices of two display units for transferring information representative of the condition of the light sources of one bank of one display unit to the light sources of one bank of the other display unit.

5. A display system as set forth in claim 4 wherein said means connected between the storage devices of two display units transfers the information as a set of signals in parallel.

6. A display system as set forth in claim 4 wherein said means connected between the storage devices of two display units transfers the information as a serial sequence of signals.

7. A display system comprising:

a plurality of segmented modules for displaying characters by energizing selected segments, a storage device including at least one bank of light sources, each light source of a bank when in a first condition corresponds to a segment of a character module to be energized,

means for selectively switching into said first condition certain of said light sources in a bank corresponding to the character to be displayed,

means for each display module for detecting said first condition of the light sources in a bank and for controlling the energization of the segments of the associated module in accordance therewith,

means for scanning each bank of light sources by the detecting and control means for each module to display the character corresponding to the detected first condition of the various light sources in a bank on each module,

further means responsive to the sensing of each light source of a bank in said first condition for producing a control signal corresponding thereto, and means responsive to said control signal for switching the light source producing said control signal from said first condition to another condition.

8. A display system responsive to a serial frequency of information signals comprising:

a plurality of segmented modules for displaying characters by energizing selected segments thereof, a storage device including a plurality of banks of light sources, each light source of a bank when in a first condition corresponds to the segment of a character module to be energized,

means responsive to a serial sequence of signals in a predetermined pattern for selectively switching into said first condition certain of said light sources of one bank corresponding to the character to be displayed,

means for each display module for detecting said first condition of the light sources in a bank in operative relationship with it and for controlling the energization of the segments of the associated module in accordance therewith,

means for scanning said one bank of light sources by the detecting and control means for each module so that the character corresponding to the detected first condition of said one bank of light sources is displayed on each module, means responsive to an information signal means for bringing another bank of light sources into operative relationship with the selective switching means,

further means responsive to the sensing of each light source of a bank in said first condition for producing a control signal corresponding thereto, and means responsive to said control signal for switch-

ing the light source producing said control signal from said first condition to another condition.

9. A display system responsive to a serial sequence of information signals as set forth in claim 8 and further comprising means responsive to each said control signal for reproducing the original serial sequence of signals used to switch the light source of the bank producing said control signals into said first condition. 5

10. A display system comprising:

a plurality of segmented modules for displaying characters by energizing selected segments thereof, a storage device including a plurality of banks of light sources, each light source of a bank when in a first condition corresponds to the segment of a character module to be energized, 10

means responsive to a serial sequence of signals in a predetermined pattern for selectively switching into said first condition certain of said light sources of one bank corresponding to the character to be displayed, 15

means for producing said serial sequence of signals comprising:

(a) a drum having a plurality of openings around the drum surface, said openings being formed in a predetermined manner in a number of tracks corresponding to character information to be produced, 20

(b) a light source adjacent each said track,

(c) means for selectively energizing one of said light sources, 25

(d) a light responsive means adjacent each said track and responsive to the illumination sensed from a corresponding opening for producing a signal, and

(e) means for moving said drum and said light responsive means relative to each other, 30

means for each display module for detecting said first condition of the lamps in a bank in operative relationship with it and for controlling the energization of the segments of the associated module in accordance therewith, 40

and means for scanning said one bank of light sources by the detecting and control means for each module to display the character corresponding to the detected first condition of the light sources of said one bank on each module, and 45

means also bringing another bank of light sources into operative relationship with the selective switching means.

11. A display system comprising:

a plurality of segmented modules for displaying characters by energizing selected segments thereof, a storage device including a plurality of banks of light sources, each light source of a bank when in a first condition corresponds to the segment of a character module to be energized, 50

means responsive to a serial sequence of signals in a predetermined pattern for selectively switching into said first condition certain of said light sources of one bank corresponding to the character to be displayed, 60

means for producing said serial sequence of serials and other signals comprising:

(a) a drum having a plurality of openings around its surface, said openings being formed in a predetermined pattern in a number of tracks corresponding to character information and in another of said tracks corresponding to start information, 65

(b) a light source adjacent each said track,

(c) means for selectively energizing one of said light sources adjacent a character information track having the character information to be produced, 70

(d) means for energizing a light source adjacent the start information track,

(e) a light responsive means adjacent each said character information track and said start information track and responsive to the illumination sensed from a corresponding opening for producing a signal, and

(f) means for moving said drum and said light responsive means relative to each other,

means for each display module for detecting said first condition of the lamps in a bank in operative relationship with it and for controlling the energization of the segments of the associated module in accordance therewith,

means for scanning said one bank of light sources by detecting and control means for each module to display the character corresponding to the detected first condition of the light sources of said one bank on each module,

means also bringing another bank of light sources into operative relationship with the selective switching means,

and means responsive to the signals produced corresponding to start information for controlling the starting operation of said scanning means.

12. A display system comprising:

a plurality of segmented modules for displaying characters by energizing selected segments thereof, a storage device including a plurality of banks of light sources, each light source of a bank when in a first condition corresponds to the segment of a character module to be energized,

means responsive to a serial sequence of signals in a predetermined pattern for selectively switching into said first condition certain of said light sources of one bank corresponding to the character to be displayed,

means for producing said serial sequence of signals and other signals comprising:

(a) a drum having a plurality of openings around the drum surface in a predetermined pattern, said openings being formed in a number of tracks one of said tracks corresponding to synchronization information, another of said tracks corresponding to start information and at least one of said tracks corresponding to character information,

(b) a bank of lamps adjacent the openings in each said track,

(c) means for selectively energizing one of said banks of glow lamps adjacent the character information track and the lamps adjacent the start and synchronization information tracks,

(d) light responsive means adjacent each of said tracks on said drum for producing a signal in response to the illumination sensed from a corresponding opening, and

(e) means for moving said drum and said light responsive means relative to each other,

means for each display module for detecting said first condition of the lamps in a bank in operative relationship with it and for controlling the energization of the segments of the associated module in accordance therewith,

means for scanning said one bank of light sources by detecting and control means for each module to display the character corresponding to the detected first condition of the light sources of said one bank on each module,

means also bringing another bank of light sources into operative relationship with the selective switching means,

and means responsive to start and synchronization signals for controlling the starting and running operation of said scanning means.

13. A plural display system responsive to serially occurring signals for producing a parade type display comprising:

a plurality of segmented modules for displaying characters by energizing selected segments thereof,
a storage device including a plurality of banks of light sources, each light source of a bank when in a first condition corresponding to a segment of a character module to be energized,
means responsive to the serially occurring signals for selectively switching into said first condition certain of said light sources of one bank corresponding to the character to be displayed,
means for each display module for detecting said first condition of the lamps in a bank in operative relationship with it and for controlling the energization of the segments of the associated module in accordance therewith,
and means for scanning said one bank of light sources by the detecting and control means for each module so that the character corresponding to the detected first condition of said one bank of light sources is

5
